[57] CLAIM

The ornamental design for a ski carrying case, as shown and described.

DESCRIPTION

FIG. 1 is a front perspective view of a ski carrying case showing our new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side view thereof;

FIG. 7 is a left side view thereof;

FIG. 8 is a front perspective view of an alternative embodiment of a ski carrying case showing our new design;

FIG. 9 is a front elevational view thereof;

FIG. 10 is a top plan view thereof;

FIG. 11 is a rear elevational view thereof;

FIG. 12 is a bottom plan view thereof;

FIG. 13 is a right side view thereof; and,

FIG. 14 is a left side view thereof.

The straps in FIGS. 3 and 10 are shown broken away for the convenience of illustration.
